UNITED STATES PATENT OFFICE.

ALEXIS F. GILLET, OF OMAHA, NEBRASKA, ASSIGNOR TO JUBILEE MANUFACTURING COMPANY, OF OMAHA, NEBRASKA, A CORPORATION.

SPARK-INTENSIFIER FOR SPARK-PLUGS.

1,169,744.

Specification of Letters Patent. Patented Jan. 25, 1916.

Application filed December 17, 1914. Serial No. 877,671.

To all whom it may concern:

Be it known that I, ALEXIS F. GILLET, a citizen of the United States, residing at Omaha, in the county of Douglas and State 5 of Nebraska, have invented certain new and useful Improvements in Spark-Intensifiers for Spark-Plugs, of which the following is a specification.

This invention relates to a spark plug attachment or electrical intensifier, and has 10 for one of its objects to provide such a frame and mounting for the intensifier or spark gap that a short circuit of the electrical charges which pass to the spark plug will 15 be prevented.

Another object is to provide an adjustable mounting for the frame so that it may be disposed at a desired angle with reference to the spark plug.

20 The invention also has reference to such a mounting for the insulating plates in the frame that they will be relieved from stresses tending to cause fracture or disintegration when they become weakened from 25 effects of the heat of the electrical charges.

With these objects in view the invention presents a novel construction, combination and arrangement of parts as described herein and claimed, and as illustrated in the 30 drawing, wherein,—

Figure 1 is a view in longitudinal section through the frame of the intensifier or spark gap, a part of a spark plug being also shown, said frame being disposed at right 35 angles to the spark plug. Fig. 2 is a view in transverse section through the connecting band. Fig. 3 is a view of one of the ends of the frame for the spark gap. Fig. 4 is a view in side elevation of the frame for the 40 spark gap, a part of a spark plug being also shown, said frame being disposed in line with the spark plug. Fig. 5 shows a side view of the connecting band mounted on the end of a spark plug. Figs. 6 and 7 respectively are views in transverse section of the outer and inner supporting blocks used 45 in connection with the band shown in Fig. 5.

Referring now to the drawing, numeral 8 indicates a spark plug, and in order that the 50 electrical charges in conjunction with the spark plug may have greater intensity for igniting the gas, and in order that an operator may ascertain, by visual examination, whether the electrical charges are being conducted to the spark plug, a frame 9 is pro-

vided for a spark gap, consisting, in part, of the pair of substantially parallel disks or circular plates 10 of electrical non-conducting material disposed end to end, each being formed to open on its side and outer 60 end with an annular recess 11, and provided with an outwardly projecting cylindrical part 12, and being formed with an annular recess 13 opening on its side and inner end, and providing an inwardly projecting cy- 65 lindrical part 14.

Numerals 15 indicates a transparent tube or sleeve adapted to be seated in recesses 13.

At 16 are indicated a pair of annular rims disposed in recesses 11 and projecting 70 outwardly of the peripheries of the disks. By means of the screws 17 which traverse said rims outwardly of the sides of the sleeve and disks, said disks may be normally pressed against the ends of the sleeve and 75 maintained in connected relation.

Numerals 18 and 19 respectively indicate 80 sparking-pins or electrodes which are threaded axially in the electrical non-conducting plates.

At 20 is indicated a circular band, provided midway between its ends with a slot 21 and an aperture 22 (Fig. 2). It may be readily connected with the outer end of the spark plug, the electrode 23 thereof traversing apertures 24 of the supporting-blocks 25 and 26, the block 25 being interposed between the end of the spark plug and said band and having a concaved surface corresponding to the curvature and for a bearing 90 upon said band. One side of block 26 is formed convexed for a bearing upon the inner side of the band, and by means of the nut 27 threaded on the electrode 23, the band may be secured upon the spark plug. 95

Numerals 25' and 26' respectively indicate supporting blocks similar to those already described. They are traversed by the electrode 18, the latter being disposed in slot 21, and by means of the nut 27' the band 20 may be compressed between block 25' and 100 26'. Since these blocks and band 20 are preferably constructed of metal they will, in conjunction with the band 20, operate to conduct the electrical charges from the 105 electrode 18 to the electrode 23.

The electrode 19 may be adjusted longitudinally so that its convergent end will be disposed a suitable distance from the corresponding inner end of the electrode 18, and 110

by means of the nut 28 said electrode may be locked or secured stationary with reference to the annular insulating plate which it traverses. By means of the thumbnut 29 5 the wire or electrical conductor 30 may be pressed against the lock nut 28.

As thus described, the pair of rims 11 and screws 17 provide a metallic over-frame for pressing the insulating plates toward 10 each other, and it will be noted that said plates are not depended upon for holding the screws 16. It is well known that the insulating parts when constructed of rubber or fiber, after a certain amount of use, become 15 decomposed and very much weakened on account of the excessive heat to which they are subjected, and one of the advantages derived by the present construction is that the disintegration or fracture of the 20 insulating plates usually caused by bolts or screws threaded in said plates will be avoided, the stresses generally sustained by the insulating plates occasioned by said bolts or screws, being directed to the metallic frame, 25 in the present instance.

The function discharged by the inwardly projecting part 14 of each insulating plate is not only to provide a support for the transparent tube, but it adds a much needed 30 thickness or length to the plate for an adequate support of the electrode threaded axially therein. This cylindrical projection is convenient in manufacture and tends to prevent vibration of the electrode. The outwardly projecting parts 14 provide adequate insulation between the metallic rims 16 and other metallic parts, to prevent a short circuit of the electrical charges. By this construction it may be said that each annular 35 rim is disposed intermediate the ends of an insulating plate or disk.

In the use of spark gaps for the spark plugs of internal combustion engines, it is not only well known that the heat causes 40 decomposition and cleavage of the insulating plates, but also that the parts are subjected to continued vibration, and sand and dust accumulates and causes a short circuit for the electrical charges, also that the spark 45 plugs are less accessible on some engines than others, and therefore the particular form now provided for the metallic plates, the particular metallic frame and the mounting of said frame upon said plates 50 and the location of the metallic frame with reference to extraneous metallic parts, and the mounting for the device which permits it to be disposed at any desired angle to the spark plug so that it may be conveniently 55 seen by an operator, are all features of advantage which will be appreciated by those 60 who use the device.

Having fully described my invention, what I claim and desire to secure by Letters Patent is,—

65

1. In a spark intensifier, the combination of a pair of electrical insulating disks disposed end to end adjacent to each other each being provided with a pair of annular recesses openings respectively on each of its 70 ends and side, a transparent sleeve disposed in one of the recesses of each disk intermediate said disks, a pair of rims disposed in the other recess and projecting outwardly of the side of each disk, keepers disposed outwardly of the sides of the disks and connected with said rims for pressing the disks against the sleeve, and a pair of electrodes formed as screws disposed axially of and traversing the disks, each being provided, 75 adjacent to its outer end, with devices for clamping an electrical conductor.

2. In a spark intensifier, the combination of a pair of electrical insulating disks disposed end to end adjacent to each other, a 80 transparent sleeve having its respective ends disposed intermediate the respective ends of each disk, a pair of rims each being disposed intermediate the ends and projecting outwardly of the side of a disk, means on said 85 rims and disposed outwardly of the sides of the disks and sleeve for pressing the rims toward each other, and a pair of electrodes formed as screws disposed axially of and traversing the disks, each being provided, 90 adjacent to its outer end, with devices for clamping an electrical conductor.

3. In a spark intensifier for spark plugs, the combination of a pair of electrical insulating disks disposed end to end adjacent to 100 each other, a transparent sleeve disposed intermediate the ends of each disk, a pair of rims each being disposed intermediate the ends and projecting outwardly of the side of a disk, means on said rims and disposed 105 outwardly of the sides of the disks and sleeve for pressing the rims toward each other, a pair of electrodes formed as screws disposed axially of and traversing the disks, a band having a curved part with a slot 110 formed longitudinally therein, co-operative devices for mounting the band upon the spark plug, co-operative devices for mounting the intensifier on said band with one 115 of its electrodes disposed in said slot, and means on the other electrode of the intensifier for clamping an electrical conductor.

In testimony whereof, I have affixed my signature in presence of two witnesses.
